UNITED STATES PATENT OFFICE

JEFFREY JOHN WALLACE, OF AMITE, LOUISIANA, ASSIGNOR TO GULLETT GIN COMPANY, OF AMITE, LOUISIANA

DISTRIBUTOR CONVEYER

Application filed April 1, 1931. Serial No. 527,010.

This invention relates to improvements in belt conveyers adapted for use in distributors for a series of cotton gins.

The main object of the invention is to provide a distributor conveyer built up in sections of standard length which can be readily connected to each other or disconnected from each other to provide a distributor conveyer of any desired length and adapted to distribute cotton to any desired number of gins in series.

A further object of the invention is to provide distributors of this type of such material as to eliminate fire hazards and of such construction as to render the parts thereof readily accessible for replacement or repair.

Other objects of the invention will become apparent as the detailed description thereof proceeds.

In the drawings:

Figure 1 is a side elevation of the distributor conveyer adapted to be applied to a series of gins;

Figure 2 is a plan of the conveyer illustrated in Figure 1;

Figure 3 is a central longitudinal section through the conveyer illustrated in Figures 1 and 2;

Figure 4 is a fragmentary front elevation to an enlarged scale of a central section for connecting different sections of the conveyers to each other;

Figure 5 is a vertical transverse section taken on the line 5—5 of Figure 4;

Figure 6 is a side elevation to an enlarged scale of a belt tightening adjusting mechanism forming part of this invention;

Figure 7 is a vertical longitudinal section taken on the line 7—7 of Figure 6; and

Figure 8 is a perspective view of one of the side plates of the aforesaid central section.

As shown in the drawings, the invention comprises a casing 1 having side walls 2 and 3, suitably spaced apart by bottom sections 4 to provide discharge openings 5 adapted to feed cotton from the said casing into the hoppers 6 leading to the gin connected therewith. The sides 2 and 3 are formed of stiff sheet metal and have their upper edges suit-

ably flanged to receive a cover 7. The casing may be made up of any desired number of sections having their ends suitably flanged and provided with means for connecting one section to another. The number of sections in any distributor outfit will depend upon the number of gins intended to be supplied by the said distributor.

In Figures 1 and 2 of the drawings, the distributor is shown as comprising three main sections A, B and C, each of which may be built up in as many separate parts as may be found convenient for handling. The section A is shown as provided at one end with bearings 8 and 9 for a driving shaft 10, the said bearings being suitably secured to the side walls 2 and 3 of the section A.

The center section B has reinforcing plates 11 and 12 attached to the sides thereof by riveting or welding in order to stiffen the sides of this section. The plate 11 and the side of the section to which it is attached, are provided with slots 13 through which extend a shaft 14 suitably journaled in bearings to be described hereinafter. The reinforcing plate 11 has Z-shaped members 15 and 16 spaced apart on opposite sides of the slot 13 and parallel thereto, in order to receive a housing 17 to which the bearings 18 and 19 are suitably secured.

The housing 17 is slidably mounted between the Z-shaped members 15 and 16 in order to provide for tensioning the conveyer belt by suitable adjustment of the said housing and the shaft carried thereby in one direction or another on the said center section B.

A similar pair of Z-shaped members 20 and 21 are secured suitably to the reinforcing plates 12 and parallel to the slot 22 formed in the plate 12 and the side 2 of the center section B. A housing 23 similar to the housing 17 is slidably mounted between the Z-shaped members 20 and 21 and bearings 24 and 25 are suitably formed on the housing 23 for the shafts 14 and 26 which extend slidably through the slots 13 and 22.

The bearings on the housing 23 are spaced apart the same distance as the bearings on the housing 17 so that the shafts 14 and 26

are constantly parallel to each other and at a fixed distance apart.

A conveyer belt pulley 27 is fixed to the shaft 10; and a similar pulley 28 is fixed to the shaft 14, the said conveyer belt 30 being provided with the usual steel spikes 29 for moving the cotton along the casing 1. The shaft 10 is the driving shaft and the shaft 14 may be shifted lengthwise of the slots in the sides of the center section B to regulate the tension of the conveyer belt 30.

The end of the section C remote from the center section B has the sides thereof provided with reinforcing plates 31 and 32 suitably riveted or welded to the sides 2 and 3 of the section C. These reinforcing plates and the opposite sides of the section C are slotted to permit lengthwise adjustment of the shaft 33 toward and from the center section B. 20 The bearings 34 and 35 for the shaft 33 are mounted in the furcations 36 and 37 of a yoke member 38. The opposite sides of the section C are provided with Z-shaped reinforcing members similar to those on the center section to permit the sliding movement of the furcations 36 and 37 of the yoke member 38.

The shaft 33 carries a pulley 39; and a conveyer belt 40 extends around this pulley and 30 around a pulley 41 which is suitably secured to the shaft 26 of the center section B. The belt 40 is provided with spikes similar to those of the belt 30 and serves the same purpose.

35 The yoke 38 is provided with a boss 42 in which the head 43 of a screwthreaded bolt 44 is suitably secured. The bolt 44 extends freely through an aperture 45 in a wall 46 having its opposite ends suitably secured to the side walls 2 and 3 (see Figure 7). A nut 48 is threaded onto the bolt 44 and is provided with an annular groove 49 which retains the nut rotatably in the aperture 45 of the wall 46. The nut 48 has a bevel gear 50 formed thereon; and this bevel gear 50 meshes with a similar gear 51 which is secured to the end of the shaft 52 suitably journaled in the wall 3 of the section C and in a brace 53 which extends across the Z-shaped 40 members on the reinforcing plate 31. The shaft 52 has a hand wheel 54 secured to the end thereof, the said hand wheel being adapted by its rotation to operate the bevel gear 50 and nut 48 for adjusting the yoke 38 in one direction or the other to regulate the tension of the conveyer belts.

As clearly shown in Figure 2 of the drawings, the shafts 14 and 26 are provided with sprockets 55 and 56, respectively, which are connected operably to each other by an endless sprocket chain 57. It will be apparent from the drawings that when the yoke 38 is adjusted by means of the hand wheel 54 it will cause the belt 40 to pull the pulley 41 and thereby move both shafts 26 and 14

to tighten the belt 30. It will be obvious, too, that the shaft 10 drives the conveyer belt 30 and through the sprocket wheels 55 and 56 and chain 57, also drive the conveyer belt 40 and in the same direction.

70 The hoppers 6 are provided with any suitable valves to control the flow of cotton from the conveyer distributor; but preferably are provided with valves and valve operating mechanism of the type disclosed and claimed in my copending application for distributor hopper, Serial No. 524,372, filed March 21, 1931. As shown particularly in Figure 5 of the drawings, this valve control comprises a pair of plates 58 and 59 rotatably mounted by means of the shafts 60 and 61 in recesses 62 and 63 formed in the lower part of the hopper 6. These valves are normally opened and are adapted to be closed manually by any suitable form of linkage to shut off the flow 80 of cotton through the hopper 6 when desired.

85 The valve plates 58 and 59, when closed, meet substantially at the center of the hopper 6 and when opened drop the cotton through the center of the hopper 6 onto the center of the feeder drum to produce a uniform distribution over said drum. The mounting of the valve plates in the recesses permits an unobstructed flow of the cotton when the valves are in open position as shown in Figure 5 of the drawings.

90 The upper stretch of each conveyer belt is supported by a plate or board 64 which is secured between the sides 2 and 3 of the casing 1 in any suitable manner. This board 100 is made of wood or any suitable insulating material in order to prevent the spikes in the distributor belt from coming in contact with any metallic part which might cause sparks and thereby set fire to the inflammable 105 material passing through the conveyer casing. The lower side or bottom of the casing is formed of boards 4 for the same reason, that is, to prevent the tips of the metal spikes from contacting with any metallic parts 110 which would also cause a fire in the contents of the casing.

115 The manufacture of the casing in sheet metal lends itself to ease of construction and to permanency of the structure, while the arrangement of insulating material wherever there is danger of metallic parts coming in contact with each other, diminishes fire hazard; thereby retaining all the advantages of a metallic construction with those of the 120 ordinary wooden type of distributor.

125 The particular valve arrangement illustrated in Figure 5 of the drawings is of great advantage inasmuch as it delivers the cotton to the center of the feeder drum, allowing a greater spread of the cotton as it is carried over the screen in the back of the feeder, thereby permitting better cleaning and less opportunity for choking the feeder.

130 While I have shown only two distributor

belts in the same casing, it will be quite obvious that the number of belts will depend upon the number of gins to be fed by the conveyer system; and it is obvious that the section may be multiplied indefinitely so long as the last section is provided with a belt tightening device while the intermediate sections are connected to each other by idlers and drive sections similar to the center section B.

What I claim is:

1. An endless belt conveyer distributor comprising a sheet metal casing, a pulley journaled in one end of said casing, means for rotating said pulley, the other end of said casing having the side walls thereof provided with slots, a pulley mounted to slide in said slots, means for moving the last named pulley in said slots, the opposite walls of said casing intermediate the ends thereof being provided with slots, a pair of pulleys slidably and rotatably mounted in the last named slot, means for connecting said pulleys to maintain them in parallelism and at a fixed distance apart during their sliding movement, and means for rotatably connecting one of said pair of pulleys to the other.

2. An endless belt conveyer distributor comprising a sheet metal casing having a center section detachably connected to the remaining sections of said casing, a reinforcing plate connected to each wall of said center section, guideways mounted on the opposite reinforcing plate, housings slidably in each guideway, and a pair of pulleys journaled in said housings parallel to each other, and means for imparting the rotation of one pulley to the other.

3. In a conveyer distributor in which a plurality of endless belt conveyers are associated in alignment, a combined driving and driven connecting unit comprising two parallel spaced shafts, conveyer pulleys on said shafts, side members each having spaced journals for said shafts, means for mounting said side members to slide in alignment with the conveyer belts and driving means associating said shafts.

In testimony whereof I affix my signature.

JEFFREY JOHN WALLACE.
